3 Claims. (Cl. 60—39.65)

ABSTRACT OF THE DISCLOSURE

The disclosure of this invention pertains to a flame tube for a gas turbine engine combustion chamber in which a heat retaining hollow member is positioned in the upstream end of the flame tube so that primary combustion takes place within said member and the inner surface of said member is isolated from all cooling air whereby said member becomes very hot and this fact will in itself promote combustion.

This invention concerns a flame tube, e.g. for a gas turbine engine combustion chamber.

According to the present invention, there is provided a flame tube for gas turbine engine combustion equipment having an inlet at its upstream end through which a fuel/air mixture may be supplied to the flame tube, the inlet having a maximum diameter which is substantially less than the maximum diameter of the flame tube, a one-piece part-spherical member formed of a ceramic material which is mounted at the upstream end of the flame tube and within which, in operation, primary combustion occurs, the upstream end of the said member communicating with the said inlet but being otherwise completely unapertured, the downstream end of the said member having a diameter which is substantially the same as the said maximum diameter of the flame tube, and means through which a flow of cooling air may be supplied to the internal surface of the flame tube, completely bypassing the interior of the said member so that the latter remains completely uncooled in operation.

Combustion is promoted in the flame tube of the present invention by reason of the fact that the said part-spherical member becomes very hot since cooling air does not flow over its internal surface.

The said member is preferably formed of densely sintered silicon nitride. Thus the specific gravity of the sintered silicon nitride is preferably at least 3.0.

The flame tube is preferably substantially cylindrical, although the present invention is also applicable to an annular flame tube.

The flame tube preferably has a plurality of axially consecutive sections with annular gaps therebetween, the annular gaps being such that cooling air supplied thereto will flow over the internal surfaces of the respective sections.

The said member may be mounted within the upstream one of said sections and may be connected thereto by at least one expansion joint.

The invention also comprises a combustion chamber for a gas turbine engine in which there is mounted at least one flame tube as set forth above.

Additionally, the invention comprises a gas turbine engine having such a combustion chamber.

The invention is illustrated, merely by way of example, in the accompanying drawings, in which:

FIGURE 1 is a diagrammatic view, partly in section, of a gas turbine engine having a combustion chamber provided with flame tubes in accordance with the present invention, and

FIGURE 2 is a broken-away sectional view on a larger scale of part of one of the flame tubes of FIGURE 1.

2

In FIGURE 1 there is shown a gas turbine jet propulsion engine 10 having an engine casing 11 in which there are mounted in flow series a compressor 12, a combustion chamber 13, and a turbine 14, the turbine exhaust gases being directed to atmosphere through an exhaust duct 15.

Mounted in the combustion chamber 13 are a plurality of angularly spaced apart substantially cylindrical flame tubes 16.

Each of the flame tubes 16 has a plurality of axially consecutive sections 20, an annular gap 21 being provided between the downstream end of each section 20 and the upstream end of the adjacent section 20. Mounted in each of the annular gaps 21 is a corrugated annular member 22 which serves to space the adjacent sections 20 from each other.

Air which has been compressed by the compressor 12 is supplied to the exterior of the flame tubes 16 and enters the annular gaps 21 so as to flow over the internal surfaces of the sections 20. This is indicated by the arrows 23.

The most upstream of the sections 20 has a reduced diameter portion 24 at its upstream end which forms an inlet through which a fuel/air mixture may be supplied to the flame tube. As will be seen from FIGURE 2, the diameter of the inlet 24 is substantially less than the maximum diameter of the sections 20.

Mounted in the inlet 24 is a swirl device 25 for effecting mixing of air from the compressor 12 with fuel which is delivered thereto from a fuel manifold 26.

Mounted within the said upstream section 20 is a one-piece member 30 which is part-spherical in shape. The member 30 has a sliding connection with expansion joints 31 which are mounted in the upstream section 20. Apart, however, from the apertures to receive the expansion joints 31, and apart from its open upstream and downstream ends, the member 30 is un-apertured.

The member 30 is made of ceramic material such as densely sintered silicon nitride (e.g. of specific gravity 3.1 to 3.2), its construction being such that it will withstand the heat from the primary combustion which in operation occurs within it.

If desired, the member 30 may have its downstream end extending to the downstream end of the upstream section 20.

The upstream end of the member 30 communicates with the inlet 24 and has a diameter which is substantially the same as the diameter of the inlet 24. The downstream end of the member 30, however, has a diameter which is substantially the same as the maximum diameter of the flame tube 16.

The upstream section 20 has apertures 32, through which a supply of cooling air may flow to the internal surface of the upstream section 20.

As will be noted, however, the construction of the flame tube is such that no cooling air will flow over the internal surface of the member 30. The member 30 is therefore maintained very hot from the primary combustion occurring within it, and this will, in itself, promote combustion.

I claim:

1. A flame tube for gas turbine engine combustion equipment having an inlet at its upstream end through which a fuel/air mixture may be supplied to the flame tube, the inlet having a maximum diameter which is substantially less than the maximum diameter of the flame tube, a one-piece part-spherical member formed of a ceramic material which is mounted at the upstream end of the flame tube and within which, in operation, primary combustion occurs, the upstream end of the said member communicating with the said inlet but being otherwise completely unapertured, the downstream end of the said member having a diameter which is substantially the same as the said maximum diameter of the flame tube,

and means through which a flow of cooling air may be supplied to the internal surface of the flame tube, completely by-passing the interior of the said member so that the entire inner surface of said member is completely isolated in operation from any cooling air.

2. A flame tube as claimed in claim 1 in which the flame tube comprises a plurality of axially consecutive sections which define annular gaps therebetween, the said member being mounted within the upstream one of said sections, there being provided at least one expansion joint to connect the said member to the upstream one of said sections.

3. A flame tube as claimed in claim 1 wherein said ceramic material is silicon nitride.
